FIG. 3

INVENTOR:

ARTHUR D WALKER
By Whitley and Buckman
ATTORNEYS

UNITED STATES PATENT OFFICE.

ARTHUR D. WALKER, OF MINNEAPOLIS, MINNESOTA.

CARD-GAME SCORER.

Application filed October 4, 1920. Serial No. 414,897.

To all whom it may concern:

Be it known that I, ARTHUR D. WALKER, a subject of the King of Great Britain, residing at Minneapolis, in the county of Hennepin and State of Minnesota, have invented certain new and useful Improvements in Card-Game Scorers, of which the following is a specification.

My invention relates to card games scorers. An object of the invention is the provision of a device intended particularly for scoring the points in the game of auction bridge so as to eliminate the present method of scoring by means of paper and pencil. A further object is to provide a device in which the total scores and number of games standing to the credit of the players may be seen at a glance at any stage of the game. In the present form of auction score sheet, the game points are recorded below the line and the honor points, slams, doubles, etc., are recorded above the line. It frequently happens that the players will inquire how the game stands, necessitating the addition of the columns of figures from time to time. When my device is used, such interruptions are avoided; and it is not necessary to provide paper and pencils. Although my scorer is intended particularly for scoring the game of bridge, it may also be used in playing other games of cards such as "500", whist, cribbage, or any card game which necessitates the keeping of a score.

The full objects and advantages of my invention will appear in connection with the detailed description thereof, and the novel features embodied in my inventive idea are particularly pointed out in the claims.

In the accompanying drawings, Fig. 1 is a plan view of an individual scoring device suitable for three-handed games, each player recording his own score on one of these devices as the game progresses. Fig. 2 is a plan view of a device for scoring four-handed games. Fig. 3 is a plan view of a device similar to that shown in Fig. 2 but made up in folder form. Fig. 4 is a view in section on the line 4—4 of Fig. 1.

Referring to the particular construction shown in the drawings, the form of invention shown in Fig. 1 will first be described but the same reference numerals will be used for all of the forms so far as applicable. The numeral 10 designates a base member which is made of suitable sheet material such as card board or celluloid. Printed or

otherwise formed upon the lower portion of the base member is a double row of numerals, the first row beginning with zero and extending as high as may be considered desirable, for instance, — up to 17. The second row extends from zero up to 9, corresponding to the numbers in the first column and the remaining spaces opposite the numerals in the first row are each marked "Zero." Pointers 12 and 14 are adapted to be slid along these two rows, respectively. Printed or otherwise formed upon the upper portion of the base member is a semi-circular scale 16 provided with numbers indicating divisions extending from zero to 100. A pointer 18 pivoted to the base member at 20 may be turned to indicate any one of these numbers. Upon the upper portion of the base member is also provided a column of figures starting with zero and with each succeeding number, one hundred greater than the preceding number. A pointer 22 is slidably mounted so as to be capable of indicating any one of these numbers. Fig. 4 shows a convenient method of slidably mounting the pointer 22, which method may be employed for all of the other slideable pointers. Secured to the base member is a strip 24 of flexible material, one side of which is upwardly curved to form a spring member 26 which is provided with a slot 28. The rear end of the pointer 22 is provided with a curved rib 30 engaged underneath the spring member 26 by means of which the pointer is frictionally held in place. A stem 32 attached to the rib 30 and extending through the slot 28 provides for sliding the pointer. A dial 34 printed or otherwise formed upon the upper portion of the base member and provided with a pointer 36 pivotally attached at the center of the dial is used for entering the number of games. In order that the device may be used for playing the game of "500", the base member is preferably provided with a hole 38 adjacent which is a pivoted member 40, so that the hole may be covered or uncovered to indicate whether the player's score is based on the fact that he is this amount "out of the hole" or this amount "in the hole." Fig. 2 shows a form of invention in which the general arrangement is similar to that shown in Fig. 1 but is provided with duplicate scoring devices on the left-hand and right-hand sides, so that the scores of partners may be recorded for four-handed games. The two sides may be

printed in different colors, for instance black and red for convenience in designating the two opposing sides of players in which case they will be designated as red and black instead of as at present by the terms "we" and "they." The parts on the right-hand side of this form of the invention which correspond to similar parts on the left-hand side are designated by the same reference numerals with the prime mark added. The two pointers 22 and 22' in this form are on opposite sides of the same scale. Fig. 3 shows a form of the invention similar to that shown in Fig. 2 but arranged in folder form, the two side portions being capable of being folded together upon the line 42. In order to permit folding, separate columns are provided for the two pointers 22 and 22'.

The operation and advantages of my invention will be obvious from the foregoing description. Game points are recorded below the middle line of the device by the pointers 12 and 14. In the game of bridge, thirty points must be scored to win a game but it frequently happens that over thirty points are scored in a single game. For instance, a declarant bidding four spades and making his bid, would record thirty-six points. These points would be registered by moving the pointer 12 to the figure "3" in the first column and the pointer 14 to the figure "6" in the second column as shown at the right in Fig. 2. The winner of the game would then record one game on the scale 34 and place thirty-six points to his credit on the semi-circular scale 16, the latter being also used to register honors, slams, doubles, and rubbers. For example, the winner just referred to may hold simple honors in spades and would, therefore, be entitled to register eighteen points in the semi-circle, thus making a total amount to be registered on this scale of fifty-four. When

the total points to be registered on the semi-circular scale amount to one hundred or over, the one hundred points are transferred to the column adjacent the pointer 22 which is slidably moved to indicate this amount. If the amount scored at this time is exactly one hundred, then the pointer 18 is turned back to zero, but in case the last score exceeded one hundred, the excess over this amount is recorded by setting back the pointer 18 the proper amount. It will be readily seen that the total in the column adjacent the pointer 22 plus the total indicated on the semi-circular scale will record the gross total at the end of each game of the parties participating therein, and will avoid the necessity of adding the figures to ascertain how the game stands, thus saving time. At the end of the play, the dial 34 will indicate the number of games won and the total score of each party can be seen at a glance by observing the position of the pointers 22 and 18.

I claim:

A card game scorer comprising a sheet-like member, a strip of flexible material secured along one of its edges to said sheet-like member, the body of said strip being curved to provide a spring member in spaced relation to said sheetlike member, a pointer resting upon said sheetlike member, a curved rib upon the rear of said pointer engaged by the curved portion of said strip, and a stem extending out from said rib, said stem passing through a longitudinal slot in the curved portion of said strip whereby said pointer may be slid for the purpose of bringing it into register with anyone of a succession of numbers placed adjacent said strip.

In testimony whereof I hereunto affix my signature.

ARTHUR D. WALKER.
